UNITED STATES PATENT OFFICE.

GEORGES D'INFREVILLE, OF NEW YORK, N. Y., ASSIGNOR TO NATIONAL BELL TELEPHONE COMPANY.

TELEPHONE SYSTEM.

SPECIFICATION forming part of Letters Patent No. 234,578, dated November 16, 1880.

Application filed March 9, 1880. (No model.)

To all whom it may concern:

Be it known that I, GEORGES D'INFREVILLE, of the city, county, and State of New York, have invented a new and useful Improvement 5 in Telephone Systems, which invention is fully set forth in the following specification.

The object of my invention, broadly stated, is to accomplish with a single wire, emanating from a central office and passing through several 10 outside stations, much or all of what is now accomplished with a separate wire from said central office to each of said stations.

By my invention, when used on a single wire connecting several stations with the central 15 office, any station can call the central office and be automatically warned that its call has reached the said central office, and then communicate with the latter without interference from other stations. The central office can put 20 itself in connection with any station at pleasure and call or communicate with that station to the exclusion of the others. The central office, while retaining at all times full control of the line, can call two stations successively, 25 which can then be put in communication with each other, irrespective of their relative situation on the line, or it can at the same time put several stations in communication each with the one next to it on either side along the same 30 line of wire, so that said stations can communicate with each other without interference. The invention is applicable to each of these purposes separately, and the whole or several parts can be combined with other known or 35 suitable systems and forms of apparatus. It is also one of the objects of the invention to effect the above results with devices which are simple and uniform, or nearly so.

The invention is intended for telephone- 40 lines, district and fire-alarm telegraphs, buildings, and can be applied to burglar-alarms, railway-signaling, telegraph-lines, &c.

The nature and operation of my apparatus are as follows:

45 At the central office I provide a number of cells of battery so arranged that, either by reversal or by connecting different ends of the whole or of different sections of the battery to line, I can send a current of either polarity 50 desired. I provide at the central office and at

each station a polarized relay, whose armature can move between two stops or contact-points having different electrical connections. For example, at each station outside of the central office one of said stops connects with the line 55 leading to a more distant station, while the other connects with the ground and can make such station for the time being the terminus of the electric circuit. All these armatures are worked by polarized relays, and can therefore 60 be thrown against one stop or the other, according to the polarity of the current sent over the wire from the source of electricity at the central office. Normally all these armatures are in contact with the line-stops; but by de- 65 pressing a key at either station or at the central office the main battery sends over the line a current of a certain polarity, which works an annunciator at the central office to call the attention of the attendant and throws over to 70 the other stops the armature of the polarized relay at the central office and at every station in the system. The movement thus caused in the armature at the central office establishes a new set of electrical connections with the line- 75 wire and throws upon it a current of different polarity. This current, passing through the line, closes it to the first station, there passes through the armature of its polarized relay, through its ground-stop, to earth; but its spe- 80 cific polarity is such that it at once throws the armature of that station to its line-contact, and thus opens a path for the current and causes it to pass to the next station, where the same operation is repeated, and so on at each station 85 successively, thus in turn making each station the terminal point of the line until the signaling or desired station is reached. I then have a line from the central office grounded through the ground-wire at that station and cut off from 90 the ground-wire at each intermediate station. I place the signaling apparatus (telephone, telegraph-instrument, bell, or other alarm) of each station in its ground-wire, and I therefore arrive at a condition of things in which the cir- 95 cuit from the central office passes to ground through the instrument at the calling-station and is disconnected from the ground-wire (which includes the instrument) at each intermediate station. I then have a circuit over 100

which I can interchange conversation or other signals between the central office and the station calling. In like manner I can from the central office set into operation the batteries thereof, so that they shall first throw all the armatures of the outside stations to their ground-contacts, and then, by a current of opposite polarity operating on said polarized relays, as before stated, pick them up and replace them one by one on their line-contacts at each successive step, placing the stations one after another in circuit with the central office. By suitable and convenient means at the central office the operator there attending can arrest this operation at any desired station, and thus place himself in direct circuit with that station, there sending the current to earth through the ground-wire, and therefore through the instrument placed in such ground-wire. The circuit being thus established, he can, by any convenient signaling or other electrically-worked apparatus, communicate with the station so selected.

My invention also consists in various forms or modifications of apparatus and combinations of apparatus or devices necessary or convenient for its operation, and which enable the operator at the central office to attain some results in addition to those thus indicated.

Thus, for example, he can not only put the central office in communication with any outside station, but can put any station in direct communication with any other.

In order more fully to explain the invention and the manner of carrying the same into effect, I proceed to describe a form of apparatus in which the same is embodied, reference being had to the accompanying drawings, which form a part of this specification.

Similar letters of reference indicate corresponding parts.

Figure 1 represents the part of the invention by which a station can call the central office. This part, when employed separately, is used mostly for district or fire-alarm telegraphs. The central office, C. Off., and two stations, A and B, only are represented. The invention is not limited to any particular number of stations. Practice and the requirements of the service will determine how far their number may be safely extended; but any more stations than represented would be connected and disposed like the two stations A and B.

Figs. 2 and 3, and Fig. 4 show different modifications of the electro-magnetic arrangement in the dial-indicator.

Fig. 5 shows an improved call-key to replace the key shown in Fig. 1 at the different stations.

Figs. 6 and 7 represent a suitable manner of constructing the district-boxes at the different stations.

Fig. 8 is a diagram showing an apparatus employed in connection with the dial-indicator for rendering constant the resistance of the portion of the line worked from the central

office and for dispensing with the resistances at the several stations.

Fig. 9 represents an arrangement whereby one battery may be used in place of the two shown in Fig. 1.

Fig. 10 represents the part of my invention by which the person in charge at the central office can call any station exclusive of the others, and also the disposition by which the intercommunication between the stations above referred to can be established. In Fig. 10 the system has been illustrated in connection with the use of telephones. It is not, however, limited to such use, as other well-known signaling-instruments could be used.

Fig. 11 is an enlarged view of the key shown in Fig. 10, which is a cheaper and stronger form of the key illustrated in Fig. 5.

Fig. 12 shows the manner in which the Hughes escapement may be made to take the place of the polarized relay at the central office, and Fig. 13 an arrangement of spring-jacks whereby the same telephone at each station may be employed for communicating in either direction over the line.

In Fig. 14 a more convenient position for the condenser and also a modified arrangement of switch for connecting a larger battery gradually to line are represented.

In Fig. 15 the manner in which the condenser at the central office may be replaced by a small one at each station is shown.

In Figs. 16 and 17 are shown keys of another form for use at the stations, and in Figs. 18, 19, and 20 apparatus located at the central office, accomplishing, among others, the result for which the condenser represented in Figs. 10, 14, and 15 is employed.

Fig. 21 represents a relay which may be used at the central office and the stations in place of the relays shown in Fig. 1, and Figs. 22 and 23 forms of relays which may be used in the apparatus shown in Fig. 10 in place of the relays therein represented.

Referring particularly to Fig. 1, C. Off. is the central office, from which the line-wire L goes to the station A. It passes through the instruments of that station and emerges from it, as represented by L', to go similarly through the instruments at station B. If there are other stations, they are connected by a line, L², and so on according to the number of stations, and at the last station there is no further line-connection; but the left-hand or line-contact point corresponding to m' and m² will have a ground-connection through the key when closed, and the other, corresponding to n' and n², a direct and permanent ground-connection, as shown in the full lines at stations A and B, Fig. 1.

At the central office there is an apparatus for this line composed of four parts—viz., a polarized relay, R, an alarm, Hg, a dial-indicator having a pointer, P, and operating-magnet M, or instead of the indicator some other well-known signaling or recording instrument

—as, for example, a Morse or chemical register or a printing-telegraph—and one or two main batteries. The connection between these several parts will be explained hereinafter. For every separate line-wire emerging from the central office there is a set containing or composed of the said four parts. With the arrangement shown in Fig. 1 it may be possible, however, to work several lines from the said batteries, which are represented by X and Y, and even to use the same indicator or register for several circuits, keeping, however, a distinct polarized relay, R, and a distinct alarm, H g, for each circuit. The practicability of this operation will depend upon the number of calls likely to be made within a given time upon the different wires.

Station A includes a polarized relay, R', of the same dimensions as the polarized relay R, 20 and a key, K'. In its ground-wire an artificial resistance, r^2 , may be inserted for the purposes hereinafter explained.

Station B is arranged like station A, except that the resistance r^2 in its ground-wire, if used, 25 is less than r' , as will be also explained hereinafter.

The line-wire L^2 from station B should remain open or be omitted if there are no more stations on the line. Otherwise the line runs 30 through all the stations in the same manner, and they are all disposed like the two above-mentioned stations A and B, except that the resistances in the ground-wires, if used, should successively decrease until the last one, which 35 is *nil*. Each of these resistances should equal the resistance of all the line (instruments included) between its station and the farthest station, including the relay at the last station. The line-wire L^2 on the line-wire emerging 40 from the last station can, where practicable, return with advantage to the central office, C. Off., for a reason explained hereinafter.

At central office, C. Off., from the ground-plate G emerges the ground-wire, which is 45 connected at o between the main batteries X and Y. The two batteries have about the same number of cells and are so arranged that were the ground-wire disconnected they would form a single battery with all its cells in tension—that is to say, the positive plate of the battery Y is connected at o to the negative plate of the battery X. The wire from the negative pole of the battery Y goes to the electro-magnet M of the dial-indicator, thence to 50 the contact-point n in the polarized relay R. The wire from the positive pole of the battery X goes to the electro-magnet H, which is part of the alarm, the gong of the alarm being represented by g. I prefer to use here the well-known electro-magnetic escapement of Hughes' 55 printing-telegraph, though some other well-known form of alarm could be used. This escapement consists of a Hughes magnet with soft-iron armature, arranged to move by a strong spring when the magnetism ceases or diminishes, and by its movement release or move clock-work.

On leaving the electro-magnet H the wire runs to the bobbins of the polarized relay, R, which in the drawings is a Siemens polarized 70 relay. In this relay the armature is preferably pivoted near to the pole-pieces, and its free end is prolonged by a spring, which with a large range of motion moves between the two contact stops m and n. Opposite the heavy part 75 of the armature are two limiting-stops, p q, so adjusted that the spring end makes contact at m or n, and then, yielding to the pull of the electro-magnet, allows a still further motion to the armature before it is firmly arrested by 80 the limiters p and q. The cores of the relay are made somewhat large in order to obtain a certain amount of magnetic inertia, and the spring may be made broad, like a fan, to make its motion sluggish. The pivot or hinge of the 85 armature a is connected directly with the line-wire L, which passes thence to station A, where it enters the coils of the polarized relay R', which latter is constructed like R, though with somewhat different electrical connections, 90 as appears in the drawings. On leaving the bobbins of R' the wire is connected with the hinge of the armature a', which makes contact alternately at m' and n', and is limited by stops p' and q'. The contact-stop n' is connected permanently with the ground, as indicated at G', through the resistance r' , if such be used. The stop m' is connected with the key K', and can be temporarily connected with the ground G' by the said key. It is also 100 connected with the line-wire L', leading to station B, which is a repetition of A, except that the resistance r^2 is less than r' , as already stated, the parts corresponding to R', a', p', q', m', n', K', and G' being indicated by R², a², p², q², m², n², K², and G².

The operation of the system is as follows: When at rest the armatures a a' a², &c., are all as represented in Fig. 1, being against the left-hand contacts m m' m², and the pole-pieces and armatures of the relays R R' R² are all so adjusted that each armature will remain at whatever contact it happens to be when the current which has last moved it ceases to pass. With the armatures in the 115 condition indicated no current passes, because, although there is an unbroken connection from the battery X of C. Off. through all the instruments of the different stations, there is no ground or return connection from either or 120 any of them, and the circuit is thus normally open.

The Hughes electro-magnetic escapement is adjusted in the well-known manner by means of the soft-iron armature, which can 125 be moved along the permanent magnet placed at the back of the electro-magnet, and by adjusting the tension of the retractile spring at the back of the armature. The direction of the wire in the helices of electro-magnet H is 130 such that the first current of even momentary duration which passes through it from battery X will destroy or sufficiently weaken the magnetism which holds the armature in prox.

imity to the cores, so that it abandons the armature to the action of the retractile spring, thus causing a single blow on the gong g . The clearness of the sound on the gong is insured by the proper adjustment of a back screw, which retains the solid part of the armature at such distance that the hammer placed at the end of the spring will rebound after striking the gong and keep clear of it.

10 The armature can be supplied with a tag or drop-plate, d , of any suitable material, placed at the end of a lever connected with or forming part of the armature, and a number or other mark can be inscribed upon such tag or drop-plate. This will be useful, if several such alarms are placed in the same office, to indicate to the clerk in charge which bell has been ringing.

15 As in the Hughes apparatus, it is not intended that the armature, after having struck the gong, shall be replaced in position for another blow by the magnet itself, but by the attendant or automatically, either directly or through some well-known or suitable mechanical or electrical contrivance.

20 The direction in which the coil of the polarized relay R is wound is such that a current coming from the battery X will cause the armature a to be attracted toward the contact-

25 stop n . The wire forming the coils of the polarized relays R' and R^2 is likewise wound in such direction as to cause their armatures to be attracted toward contact-stops n' n^2 , &c., when a current from battery X passes, while 30 a current from the other battery, Y , at C Off. will cause the armatures to be attracted toward the contact-stops m' m^2 , &c. The current from battery Y (except when used as part 35 of battery X , as hereinafter described, for other purposes) never passes through the coils of relay R , but through armature a directly to line.

40 It will be easy now to understand what will take place when the station A B or any other 45 desires to call. Let us suppose first station, A, to call. The key K' is depressed once and raised immediately, as in the making of a dot in the Morse system of telegraphy. This puts the 50 screw-stop m' in connection with the ground-plate G' at the same station and closes the circuit of battery X through the electro-magnet H and ground G . This causes a stroke on the gong g by the immediate release of the 55 armature of the electro-magnet H . At the same time the current passes through the polarized relay R and moves its armature, which, in passing to the other side, n , breaks, after a brief instant, its spring-contact with m to make 60 another against n . At station A, where the key has been depressed, the armature a' of polarized relay R' moves to the other side, severing, after a brief instant, its spring-contact at m' to make one at n' with the ground-wire. 65 The armature of polarized relay R , however, in making contact against stop n , connects the

negative pole of the battery Y with the line-wire L , and as soon as the armature a' , by pressing against screw-stop n' , (which will take place almost simultaneously with the contact of armature a against n , the two polarized relays being constructed alike, except as to their electrical connections,) a complete circuit exists for the current of battery Y from ground G at central office, C. Off., to ground G' at station St. A. Let us examine what this current of battery Y will cause. At the central office, C. Off., it will pass through the electro-magnet M of the dial-indicator and attract its armature, thus putting the well-known form of escapement in operation. 70 The escapement-wheel will turn under the action of a spring by half a tooth in the direction of the arrow, and the hand or pointer fixed to the toothed wheel will leave its stop s to point to the figure 1 on the dial. The current will produce no effect on the polarized relay R , because it does not pass through its coils, but through its armature a directly to the line L and to the coils of the polarized relay R' . In this relay 75 it will cause a magnetism the reverse of that just previously received from battery X' , thereby causing the armature a' to pass to the other side—viz., from the ground-stop n' to the line m' ; but in thus passing from one contact to the opposite one there is a lapse of time during 80 which the armature touches neither, and a break in the circuit is the necessary result.

85 By observing well-known proportions and adjusting the parts of the several apparatus so as to have the relays rather sluggish, as 85 already described, and on the other hand using every well-known method to render the escapement in the dial-indicator quick working, (which rapidity the drawing in Fig. 1 is not particularly intended to represent, aiming 90 chiefly to convey an exact idea of the working, &c.,) the duration of the break at the end of the armature a' is made sufficient to allow the armature of relay M at central office, 95 C. Off., to be drawn by its retractile spring 100 against its back-stop, causing the end of another tooth to escape, so that the wheel turns by another half-tooth, and the hand or pointer points now toward letter A of the dial. After the armature a' has made contact with screw-stop m' at station A the line will be open, as 105 the key K' , the depression of which closed the circuit, is supposed to have been raised immediately after depression. The electro-magnet M , at central office will therefore remain inactive, 110 and the hand or pointer will continue to point toward A. This will indicate to the attendant at 115 central office that the call comes from station A, which is the purpose of the whole arrangement shown in Fig. 1. The attendant will then, with his finger or by means of any well-known mechanical or electrical contrivance, turn back the hand or pointer against the stop s , replace 120 similarly the armature a of polarized relay R against its screw-stop m and the armature of 125 electro-magnet H against its cores, so that the whole combination will be ready to receive the 130

turn of said armature can be made known to the caller either by the click itself of the armature, or by sight, or by a visible appendage placed at the end of it, as shown by the arrow-point in Figs. 6 and 7 of Sheet 1, which represent a suitable manner of making the district-boxes to include the instruments necessary at each station, and which will be readily understood by the drawings themselves without any further description. In these boxes the cores of the relays are placed horizontally and the armature is counterbalanced.

The system is practically non-interfering. Any station on the line beyond the calling-station being cut off by the armature of said calling-station breaking the line, as explained before, cannot of course interfere, and the calling process is so rapid, on the other hand, that there is little probability of another station calling just at the same time. Still this may happen, and the would-be-interfering station might be situated between the original calling-station and the central office. Two cases, therefore, may present themselves, and I propose to show that in either the call of said would-be-interfering station cannot, by any momentary depression of an ordinary key or any depression of the special key, Fig. 5, interfere with the previous call of the original station calling first.

At the would-be-interfering station the armature of the polarized relay will either still be on the stop connected with the ground before the current from the battery Y over the line has had time to reach said polarized relay or said armature will have regained already its position against the line-stop. In the first case it is easy to see that the momentary grounding of a section of the line which is yet cut off from communication with the central office can have no effect whatever if the current of battery Y has not yet reached the section of the line permanently connected with the coils of the polarized relay of the would-be-interfering station, and if said current has reached said section of the line it will not prevent the armature of said relay from gaining its line-contact stop m' m^2 , &c. At most there can be then a slight delay in the step-by-step motion of the dial-pointer, which continues to go on as soon as the would-be-interfering key has broken its ground-connection. In the second case the momentary grounding of the line by the would-be-interfering station taking place after the armature of said station has resumed its normal position and before the armature of the original calling station has done the same can, at most, also slightly delay the step-by-step motion of the dial-pointer, which continues as soon as the ground is removed by the raising of the key at said would-be-interfering station, and an expert attendant may even detect by a momentary stop on the dial the station from which the interference proceeds.

I have previously stated that when a call

was made at any station the key there had to be simply momentarily depressed and allowed to resume its normal position; but to provide against any difficulty which might arise from keeping any key down too long I employ the key represented in Fig. 5. This key is composed of two separate levers, one straight and the other forked. It is inclosed for protection in a box, (for convenience not shown,) from which the rubber knob protrudes. In the drawings the screw-stop m' is permanently connected with the axis of the forked lever and also with a spring which presses permanently on a metallic sector, which latter has for its center the axis or pivot of the additional forked lever, so that said spring will maintain said forked lever in any position it may assume in turning around its axis within limits sufficient for the purpose. n' is connected with the straight lever. This additional forked lever is metallic. The upper branch of its fork is supplied with two contact-points, 2 and 3. One of them, 3—the nearest to the axis—is terminated by a small insulating-bushing, and does not project so far as the point placed at the extremity of the same upper branch. The lower branch of the fork has a point, 1, also terminated with a small non-conducting bushing. Said point is placed opposite the contact-point 2. There is a sufficient distance between these two points 1 and 2 to allow some play to the back part of the straight key-lever. Said lever is metallic and permanently connected with the ground through n' . In the drawings it is represented at rest under the pressure of a spring, as in a Morse key. This makes its back part (to the left on the drawings) press upon the non-conducting extremity of the point at the end of the lower branch of the fork, and to force said lower branch of the fork to press down on an outside limiter, 4, below, which limits the play of the fork in the downward direction. In such position no current can pass from m' to n' through the key. Let, now, the rubber knob be depressed, the left part of the lever will pass from the non-conducting point below to the metallic point above. (Meanwhile the fork will remain stationary, as it has no reason to move, its center of gravity being by construction on or very near its axis of suspension and the spring to the left pressing upon the sector.) The result will be that a contact will be instantly established, and that a current can pass from m' to n' . As the rubber knob is further depressed by the operator the left part of the straight lever will raise the fork of the lever by pushing against the metallic point 2. Meanwhile the communication between m' and n' continues uninterrupted. (I will remark here that it is a rubbing or friction contact.) As this motion of the knob is continued a time comes when the extremity of the left part of the straight lever reaches the insulating-point 3 on the upper branch of the fork. The effect

next call. An automatic mechanism which can be readily arranged could restore to their normal positions the pointer of the indicator and the armatures of the relay R and of the electro-magnet H in their original positions. There are some old and well-known printing-telegraphs which have such a mechanism to carry them back to unison after each letter has been printed. Supposing, now, that at station B the key K^2 is depressed and raised immediately, let us examine how the call will be received and indicated at the central office, C. Off. The momentary depression of K^2 momentarily connects m^2 with the ground-plate G^2 , and this completes the circuit, which includes battery X, relays R R' R², and ground-wire at station B. The circuit thus completed does not include the ground-wire n' to G' at station A. The positive (+) current from X thus set up, as explained before, operates the alarm H g d and moves all the armatures a a' a^2 to the right-hand stops n n' n^2 . It is able to do this because, by reason of the sluggishness with which the spring-contacts are broken, the current has time to make itself felt to the end of the line before the contacts at m m' , &c., are broken by the motion of their respective armatures. The instant this is done a new circuit is established, which passes from the negative (-) pole of battery Y, through M n a L R' a' n' , to earth at G' . This current, acting on the magnet M, releases the escapement of the indicator at C. Off., as before, and the pointer advances to 1. Having done this, the relay R', more sluggish than the indicator apparatus, becomes affected and draws the armature a' to the left-hand stop m' . The break caused by the passage of a' from n' to m' opens the circuit, releases the armature of M, and the pointer advances from 1 to A, as before. As soon as a' touches m' the circuit of battery Y is again completed, but this time through M n a L R' a' m' L' R² a^2 n^2 to ground at G^2 . The current thus set up again moves the pointer at central office another notch—viz., from A to 2—and throws the armature a^2 from n^2 to m^2 , and the break caused by the passage of this armature again permits the pointer to move another notch—from 2 to B. When this is done the pointer rests there, and as the line is then open at the calling-station B and not closed anywhere beyond, no more change takes place, and the attendant at central office perceives that it is B that has called.

Should there be more stations beyond B, the process of calling from such farther station would be the same, one complete to-and-fro motion of the armature of the indicator at central office being caused by the automatic consecutive movement of every polarized relay in the line between the calling-station and the central office, including the relay at the calling-station.

To recapitulate the operation: Each time the circuit of battery Y is completed the armature of M in the indicator is pulled by its magnet, and each time it is broken by the pas-

sage of an armature from n' to m' , n^2 to m^2 , &c., the armature of M is drawn back by its spring. Each make of this circuit at n' n^2 , &c., and each break in passing from n' to m' , n^2 to m^2 , &c., causes, therefore, a motion of the armature of M, which can be made visible or be registered at central office. The circuit is normally open, but is complete, except that there is no distant ground-connection. Depressing a key at any station grounds the line at that station and completes the circuit from the central office to the station where the key is depressed. The armatures being in the normal position of rest—that is, all to the left, on m m' , &c.—the circuit thus completed includes the battery X, the positive (+) pole of which goes to line. The effect of this is to first ring the very sensitive alarm H g d, and then immediately to simultaneously throw all the armatures and break their contacts at m m' , &c., and pull them toward n n' n^2 , &c. As soon as the armatures have moved away from m m' m^2 the battery X is cut out by the motion of the armature a , and as soon as they reach n n' n^2 the contact of a and n at central office puts the negative (-) pole of battery Y to line, and this moves the pointer one notch or half-space from a letter to a number. As this current does not pass through the coils of relay R, it does not move armature a . It does pass, however, through the coils of R' and moves the armature a' toward m' , but it does not at this instant affect any station beyond A, because the line is grounded at G' and open beyond A. The movement thus caused in the armature a' from n' opens for an instant the circuit and allows the spring of M to move its armature and the pointer connected with it another half-step on the dial. The moment a' touches m' a circuit which includes battery Y is again completed through station A to n^2 at B, and thence to ground G^2 , and this new completion of a circuit which includes battery Y moves the pointer another half-step to 2. This current has no effect on armature a , as already stated. It has no effect to move armature a' , because that is already against m' , but it serves to pull armature a^2 from n^2 to m^2 , and the break thus caused permits the retractile spring of M to again move its armature, which allows the pointer to move another half-step from 2 to B. If the person at B has previously taken his finger off his key K^2 , as he should have done, the circuit will remain open and no further change will take place in the pointer at central office; but if he keeps the key depressed too long the current so continued will move the pointer to 3, and when he takes it off will move it to C. This inconvenience will be remedied by a peculiar key which I have devised for the purpose, and which is shown in Fig. 5. It should be remarked that the calling-station receives notice by the return of its armature a' , &c., to its original position through the operation of battery Y that its call has been received by the central office. The re-

of further depression will be to sever the contact of the left branch of the straight lever with the metallic point 2, and the communication between m' and n' will be thereby broken.

5 The pressure continuing on the rubber knob, the insulating-point 1 will be brought to bear below the left part of the straight lever and stop its further progress in its upward course.

It is obvious that the continued depression 10 of the rubber knob to the right will cause no inconvenience, as the communication between m' and n' is henceforth severed, and thus the depression of this key, no matter how long continued, will only make one momentary connection. For greater safety a strong limiter is 15 placed below the knob, (or in some other convenient position,) and one push on the knob, no matter how violent, causes the key to perform all the operations I have here described 20 without injury. When the pressure is removed from the rubber knob the left part of the straight lever pushes downward the lower branch of the fork until it stops against the outside limiting-screw, 4, and the apparatus is 25 restored to its original position.

It is obvious that the insulating material might be inserted in the straight lever instead of in the fork.

In Figs. 10 and 11 I have shown some of the 30 forms of the same key which may be cheaper or stronger. The proportions should be such that the duration of the contact will be at least long enough to work the relay.

The total amount of battery-cells used in 35 Fig. 1 at the central office, C. Off., can be reduced one-half by adopting the plan shown in Fig. 9, in which the battery Z is reversed by the movement of the armature of the polarized relay R, and fulfills in turn the function of 40 battery X and that of battery Y of Fig. 1. The disposition shown in Fig. 1, however, though requiring more cells of battery, offers a greater simplicity of contacts at the armature of the polarized relay R.

45 The resistance $r' r^2$ at the different stations can be dispensed with by adding to the dial-indicator the apparatus shown in Fig. 8, which I will now describe.

Below the flat ring of the dial, where the 50 numbers and letters 1 A 2 B 3 C are marked in Fig. 1, there is at a little distance another ring of metal cut in sections, (one for each letter,) as represented in Fig. 8, and having a certain thickness—say one-eighth of an inch—55 the different sections being held in the position shown by some insulating support. These sections are connected one with the other, as represented, through resistance-coils and electro-magnets $r^* f^* r'' f'' r''' f''' r'''' f''''$, &c.

60 The electro-magnets $f^* f'' f'''$, &c., are all of the same resistance and of the same inductive power as the magnets of $R' R^2 R^3$, &c., and the resistances $r^* r'' r'''$ are respectively equal to the resistance of $L' L^2 L^3$ of the line. In 65 practice, however, they could be made all alike, averaging the resistance of each section of the line from one station to the next. The

sections should be so arranged that the break shall come between 1 and A, 2 and B, &c.

The electro-magnets $f^* f'' f'''$, &c., could be 70 dispensed with in practice if simplicity of construction and cheapness are an object. In this case they would have to be replaced by the same amount of resistance. Another way to dispense with them without sacrificing all 75 together their inductive capacity would be to wind the increased resistance-coils $r^* r''$, &c., single, instead of double, as usual. The hand or pointer of the dial in Fig. 1 carries at the same level with the lower ring of metallic sections an articulated arm, P', bearing at its end a metallic roller or wheel or rubbing-spring. The articulated arm is pressed by a spring, P², so that the wheel will roll with some pressure over the inside circumference of the metallic 80 sections of the lower ring. This apparatus is made part of the line between n and M, the roller being permanently connected with point n and the farther section with M, as indicated 85 in drawings.

The operation of the improvement is as follows: In its normal position shown in the drawing a current passing from n to M has to traverse all the resistances and magnet-coils $r^* f^* r'' f''$, &c.; but, as the hand carrying the 90 roller moves in the direction of the arrow the total resistance between n and M decreases step by step as each section is reared. For instance, when the hand indicates station A the first bobbin of resistance, r^* , and the first 95 magnetic coil, f^* , will be subtracted from the total resistance between n and M, and it will be noticed that meanwhile the resistance of the section L' of the line and of the relay R' will have been introduced in the circuit. The 100 other coils and resistances are successively cut out as the number of the stations calling or to 105 be called increases.

The purpose of the improvement is to render uniform at all times the total electrical resistance of the circuit as well as its magnetic retardations, to insure uniformity of adjustment not only at the dial electro-magnet M, but at all the stations. This object can also be attained by placing a proper resistance in the 110 ground-wire at each station, as shown in Fig. 1 at $r' r^2$, &c., as already stated. This would, of course, simplify the construction of the dial-indicator at the central office; but the total 115 amount of resistance to be used would be far 120 greater, as the first resistance-coil at station A would have to be equal to the resistance of the rest of the line, instruments included, beyond screw-stop m' . The resistance-coils at the station would have also to be frequently 125 altered whenever more stations were inserted or added to the line, while the plan shown in Fig. 8 is free from such an objection.

I will now indicate a modification of the apparatus shown in Fig. 1, by which the central 130 office can put itself in direct communication with and can call and talk with or telegraph to any station on the line.

The armatures $a a' a^2$, &c., being in the po-

sitions represented in the drawings, and the far end of the line being permanently grounded and the positive pole of battery X disconnected from the line, (in which case the system cannot serve for calling the central office from other stations,) the attendant at the central office has but to connect it again by a key or other suitable contrivance at central office to cause immediately all the polarized armatures $a a' a^2$ at all the stations, central office included, to go against their respective ground screw-stops $n n' n^2$, &c. Then the same operation takes place as described before—viz., the battery Y, being put to line, will bring back in succession all the armatures except that of the central office, from the first to the last one, against their stops $m m' m^2$, &c., thus causing, as explained before, by the successive make and break, the dial hand or pointer to indicate all the stations, from the first to the last. I will, however, observe that in this case the dial-pointer will move by half a tooth more than in the former case and indicate the figure marked on the dial just after the letter intended to represent the last station, and this because the line in the present case is grounded instead of being open, which causes the armature of dial electro-magnet M to be attracted once more after the break caused by the passage of the armature from one contact to the other at the last station.

Now let us suppose that during this successive operation of bringing back by current of battery Y the armatures to their original position there is at central office a contrivance to enable the attendant there to break the circuit of battery Y and to connect the line-wire to ground at central office after its current has had sufficient time to restore to their original position the armatures of the relays at all the stations as far as, but exclusive of, the station to be called, and before said current has had sufficient time to affect the relay at said station to be called. It is plain that the armature of the latter station will remain against its ground contact, and there will be then a direct circuit from the ground at central office to ground at the station to be called through the polarized relays at the stations situated between the central office and that station. By having, for instance, a sufficiently-sensitive polarized single-stroke bell inserted in the ground-wire at the station to be called, (and all the other stations are to be fitted up like the one which we now consider,) and by using for this bell a battery which is considerably weaker than X or Y and of the same polarity as X, and not strong enough (with the resistance of the line and relays and artificial resistances at each station, or as shown in Fig. 8) to move the armature of any of the polarized relays, the attendant at the central office can ring said bell and call said station, after which process said weak battery can be disconnected and the ground restored at central office. A telephone, for instance, can then be

inserted or switched into the ground-wire both at the central office and at the called station. Direct communication is thus established. Instead of the bell, a telephone can be kept in the ground-wire and be used for calling by means of a circuit-breaker or "buzzer" at central office. This, however, may expose the telephone to injury.

It is plain that the conversation between the central office and the station called cannot be interfered with, for the relays and their armatures at each station are placed in a closed box, and, as there is no current on the line, said armatures will keep the position they have.

The telephones at all the stations are placed on ground-wires, and said ground-wires, not being in contact with any armature except at the two communicating stations, cannot be used to overhear what is said between the stations. As for the stations beyond that which has been called, the line-wire which otherwise joins them to said station is open at the end of the armature of the polarized relay there, and they are thus cut off from any communication with the part of the line between the central office and the station with which it wishes to communicate.

I will now describe the additional features introduced in order to call any station from the central office, and which are shown in Fig. 10. The wire which is permanently attached between the battery X and the battery Y is permanently connected at its other end with the back contact-stop of a double-pointed Morse key, Q, the lever of which is permanently connected with the ground, while its front contact-stop is permanently connected with the negative pole of battery Y. The key Q carries below its front part (the part which supports the rubber finger-knob at its end) a soft-iron armature, opposite which is placed an electro-magnet, Mⁿ. One end of the wire surrounding its cores is connected with the axis of the dial-pointer, while the other end is connected with the metallic rim or circumference of the dial through a local battery, L B. Said local battery could be, for economy's sake, a part of battery X tapped for this purpose.

Around the dial, and opposite each letter or mark representing the respective stations, I place, as is well known in some forms of transmitters for dial and printing telegraphs—for example, Siemens' dial-telegraph—finger-knobs, each fixed at the extremity of a brass rod or pin passing through a hole bored in the metallic circumference or rim of the dial. Each brass rod or pin is traversed near its extremity crosswise by a smaller brass pin, or is there provided with a collar, which prevents it from getting out of the hole by the action of the retractile spring, which is placed around said rod outside the rim of the dial, between said rim and the finger-knob. The axis which carries the pointer P of the dial also carries an

arm, O, which moves in the plane of the pins Q^a, Q^b, and Q^c, and is about one station in advance of the pointer P, as shown. The axis and this arm are insulated from said metallic rim of the dial. This arm O has affixed near its free extremity, on the side toward which it moves when revolving, a V-shaped metallic spring intended to furnish a friction-contact when in its revolution it meets with one of the depressed fingers, rods, or pins projecting inside. The length of the pointer, however, is such that its solid part will itself meet with said finger rod or pin, so that it will be impossible for said pointer to go beyond the point where it is intended that it shall stop, while at the same time the contact there will be firmer.

One wire of electro-magnet M at central office, C. Off., Fig. 10, leads to contact-point n, as before. The other wire leads to the lever of a key, K_y, the back contact-stop of which is connected with the negative pole of battery Y, while its front contact-stop is connected with battery Y at or about the middle, or rather at such point between its cells that the number to the right in the drawings shall be less than the number of its cells at the left, as circumstances may require. This latter precaution is taken for the following reason: The right part of battery Y, being used when key K_y is depressed to work the polarized call-bell of any station, must send to the line a current considerably weaker than the current of battery X, so that the armatures of the polarized relays will not be moved by it. The call-bells are indicated by b' b², &c.

The operation of the above-described feature is as follows: The armatures a a', &c., being on their line-contacts and the circuit closed through them, but having sufficient resistance to prevent the relays R R', &c., from being affected by the current from battery X alone, the depression of key Q adds the current of battery Y to that of battery X by transferring the ground from between them to the negative pole of battery Y, and the increased current throws the armatures of all the relays on the line against their respective ground-contact stops n n', &c., where they stay. This action will be utilized, as hereinafter explained, in establishing an intercommunication, which will enable at the same time several stations on the line to communicate each with his neighbor on either side.

If, now, before key Q is raised one of the finger-knobs around the dial—for example, that corresponding to the letter B, representing station B—is depressed and kept depressed either by the finger or by any piece of mechanism or locking device adapted to retain it depressed, (as by a slot and pin operated by giving it a quarter-turn,) and key Q is then raised, the battery Y is put to line through M, and the process of raising in succession the armatures along the line, as described before, goes on until, by the work of the dial-escape-ment, the arm O makes contact against the

end of the pin or rod affixed to the depressed finger-knob, that of Q^b in our example. This closes the circuit of the local battery L B through electro-magnet M^a, which attracts its armature, thereby causing a new depression of key Q. This in turn breaks the ground, and thus cuts off all battery from the main line. A through-circuit is thereby established between the central office and station B, and grounded at B through its ground-contact n², ready to signal or talk with B. The attendant at the central office can, by a repeated stroke on the knob of the key K_y, work the polarized bell of station B, as each such stroke introduces in the circuit the part of battery Y to the right in the drawings. A telephone or other instrument can then be inserted in the line by an automatic or some other well-known switch. Observe that the polarity of the current which rings the bell is the same as that of the current of battery X when the latter current passes over the line. This is for the following reason: The positive current of battery X can never pass over the ground-wire n' G' n² G², &c., at any station, as it is always automatically cut off by the break caused by the motion it gives to the armatures before they reach the ground-stop n', &c. The negative current of battery Y, however, passes repeatedly over said ground-wires at the stations. The polarized bell is therefore so connected that said negative current of battery Y cannot affect it. Therefore the key K_y has been so combined and arranged as to send over the line a current of the positive polarity required to work said polarized bell, but still sufficiently weak not to move the armatures of the relays between the central office and the called station against their ground-contact stops. After calling, the assistant at the central office takes hold of his telephone T, which might be ordinarily kept short-circuited by some well-known switch to save it from being spoiled. The person at the station called also takes hold of his telephone, which can be similarly protected when not in use, except in the case where the telephone itself is to be used instead of the signal-motion of the bell, as in some systems. When the connections have thus been made conversation can go on between the central office and the called station. When it is ended both replace their telephones, and the assistant at the central office replaces the apparatus in its original position by pulling out the pin Q^b and putting the pointer back to zero and then afterward moving the armature a to the stop m.

In the system first described, by which a station calls the central office, the line is open at its extremity. In the systems next described, by which the central office calls and communicates with the desired station, the line is grounded at its extremity. I will now combine both into a system uniting the results and advantages of both and some more besides. For this purpose I ground the extremity of the line

beyond the line-stop m^2 of the most distant station through a resistance, R^h , sufficiently high to so weaken the current of battery X that when it has no other ground-connection 5 the battery X, which is normally kept on, will not move the armatures away from the line-stops m m' , &c., but at the same time sufficiently low, that the addition of another battery to battery X by an appropriate key will 10 be able to cause the armatures a a' a^2 , &c., of all the polarized relays to pass to the opposite ground-contacts n n' n^2 , &c., contact n becoming connected with the ground by means of the same key. I thus have a line which at the 15 pleasure of the central office is open or closed at its extremity.

Instead of that resistance R^h , I may use any of the devices well known to electricians which leave the line practically open for some currents and practically closed for some others.

I will now describe an improved method of combining the two systems. At the extreme station (see Fig. 10) I make the polarized relay much more sensitive to a weak current than 25 any of the other relays. The resistance R^h (which, as before stated, must be so large that when it is in circuit the battery X will not work any of the relays) is between the left-hand or line stop of said relay and the ground G^2 , while 30 between the ground-stop and the ground-plate G^2 (supposing B to be the last station) the artificial resistance corresponding to r' r^2 , Fig. 1, is *nil*, or, as in the drawings, is omitted. By means of the key Q at the central office I add 35 to battery X the cells of battery Y, (which battery, for the purpose, need be no larger than is required for its ordinary work in the system first described,) and I thereby obtain on the line a current which, by reason of the large resistance R^h , will not be strong enough to work the relays at the intermediate stations nor at the central office, but will be strong enough to work the more sensitive relay at the last station. This will throw the armature at that 40 station to its right-hand or local ground-stop, (corresponding to n'), and thus first break the line which passes through the high resistance R^h and make a more direct ground. The circuit thus instantly comes into the condition of 45 the system previously described, and the current is immediately strong enough to throw all the armatures of all the relays, including that at central office, to their stops n n' , &c., just as battery X did in the system previously described. This movement of armature a to contact n throws on battery Y, by means of which the operator at central office can call the desired station, as already described. On the other hand, as battery X is all that is normally 50 on the line, and as it, by reason of the resistance R^h , has no effect to move the relays any more than if the line were open at its extremity, any station can call the central office by depressing its key and grounding the line 55 at its own station, as already described with reference to Fig. 1.

Finally, by the addition of a few simple attachments to the apparatus already described, I am enabled to obtain what I will term "direct intercommunication" between the 70 stations. For this purpose I adapt to the armature of each of the polarized relays a metallic plate or band, t' t^2 , &c., insulated from the armature-lever proper, though mechanically forming body with it. The end of said metallic band nearest to the pivot of said armature is connected with a spring cut-out provided with a hook, from which hangs a telephone, T^* , at station A, and T^{*2} at station B, and so on at other stations. The other ends of said metallic bands, when necessary, as explained afterward, come in contact with suitable stops q' at station A, q^2 at station B, &c. The screw-stop q' is permanently connected to the line screw-stop m' at station A, and q^2 to m^2 at station B, and so on at the other stations. 85

I will show first how the central office can put all the stations in communication each with the next on either side. All that is necessary to do at the central office for this purpose is to simply add for an instant the current of battery Y to that of battery X by key Q, which throws all the armatures to their ground-stops n n' n^2 , &c., and likewise makes contact between the metallic bands t' t^2 , &c., 95 and the stops q' q^2 , &c. Thus telephone T^* at A is in circuit with T^2 at B by the following circuit: G' , T^* , plate t' q' m' L' , coils of R^2 , armature a^2 , and its terminal spring-stop n^2 , bell b^2 , (which may be short-circuited, if desired,) 100 T^2 , and ground G^2 . In like manner telephone T^{*2} is in circuit with the telephone in the ground-wire of the next station beyond, if such there be, and so on, each station having one telephone in circuit with a telephone at the 105 next station to its right and another telephone in circuit with a telephone at the next station to the left.

I shall hereinafter show how one telephone can, by an appropriate switch arrangement, 110 be made to suffice for each station, instead of two.

The above method can be practically used and with great advantage and economy of time when several stations on the line at the same 115 time want to communicate with the adjoining station on either or both sides.

I will here also remark that whenever the central office puts itself in communication with any station—B, for instance—all the stations 120 beyond are put in communication each with the adjoining one on both sides. In this case the station A would alone be entirely cut out. This arises from the fact that the armatures of the polarized relays at all the stations, from B inclusive to the end of the line, are making contacts at q^2 , &c., and at n^2 , &c., which furnishes each station with a direct circuit with the adjoining one on each side, as explained before.

I will now describe how the central office can 130 put any two stations in intercommunication.

without fear of interference after the circuit has been established. For this purpose I insert in the section of the line L, Fig. 10, a condenser, J, of sufficient capacity for the particular purpose to be described. I keep this condenser ordinarily cut out or short-circuited by a switch, J^a. Between the alarm-magnet H and battery X, I place a switch, s w. When the handle of said switch is to the right, beyond the first contact-button, the battery X is disconnected. When said handle is on first button a part or section of battery X is connected. Another fraction or section of X is added when the switch-handle is on second button; and, finally, all the battery is on when the handle is on third button. There could be more buttons than represented. This device serves to put the whole battery gradually onto the line when so required.

Suppose, for instance, that it is required to have station B in private communication with a station (not shown) called "D," station C being intermediate. The central office puts itself in communication, by the method previously explained, with station D, calls it, and warns it to keep listening with its telephone, as station B wants to talk to it. This done, central office restores its apparatus and all the armatures at and beyond D to their position of rest—that is, against their line-contacts. The restoration of line through D and beyond is not, however, essential, as the current for moving the armatures to their ground-contacts at stations A B C could be allowed to pass to earth at station D. Then the central office puts itself in communication with B, calls it, warns it that D is actually listening, and orders it to take hold of its telephone T^{*2}, and after it has heard the click of its armature, or rather after a few seconds, to depress at least once its key K². This order given, the attendant at the central office puts himself again in direct communication with D, which can be done by the general method already described, or preferably as follows: Having only the armatures of the stations B and C to raise to obtain the desired result, he depresses first dial-finger key corresponding to station D, then lets go dial-finger Q^b to its usual position of rest. This breaks at the end of the arm O the circuit of electro-magnet M^u. The armature and key Q recede, the ground is re-established between X and G, battery Y is to line again, and throws armatures of B and C against their line-contacts m², &c. Then, the key Q being again depressed by the attraction of M^u on account of the circuit of L B being closed by the end of the arm O meeting the depressed dial-pin, the battery Y is again cut off, and the direct ground for the main line restored at the central office through a n M K^y Q G. The attendant at the central office switches off battery X by means of s w, disconnecting the whole of it from magnet H. He replaces armature a against contact m, opens condenser cut-off switch J^s, replaces dial-pointer to zero, (the order in which the two preceding opera-

tions are performed is immaterial,) and finally he switches in gradually battery X by means of s w. This could be done in some other well-known manner—for instance, by using a large resistance between battery X and magnet H, or near the condenser, and decreasing it gradually by an appropriate switch. This puts battery X gradually to line through condenser J without causing any current to the line, which current would be produced were said battery X suddenly wholly connected to condenser J. The line is now open at J, so that no constant current from battery X can pass; but as soon as station B, as previously ordered, depresses its key K² a sudden impulse from battery X (which the condenser J is large enough to transmit) goes through the line as far as ground G² at station B. This impulse throws armatures a a' a² against their contact stops n n' n², when battery Y is suddenly put to line through condenser J and restores immediately, by an impulse through said condenser, the armature a' against the line-contact stop m', and the pointer of the dial moves as usual. The attendant must, as soon as he puts the battery X to line by switch s w, depress finger-key Q^b on the dial, because a little before the armature a' touches m' the battery Y must be cut off by key Q, and the contact of the arm O with Q^b effects this. The desired result is now obtained. Station B is in communication with station D, while the central office is itself in communication with station B.

It will be observed in the foregoing description that the armature a'' of the alarm H^g, Fig. 10, is caused to move to the stop n'' by its retractile spring when the magnetism of H is destroyed or weakened by battery X at the same time that armature a moves to n, and that the armature a'' may be returned to p'' at the same time that a is returned to m. I can therefore dispense with the relay R by connecting the line-wire L with a'' instead of a, the wire from battery X with m'', with which a spring is connected so as to bear against the end of the armature a'' to complete the circuit when said armature rests against p'', and the wire from M with n'' instead of with n. I have omitted these connections from Fig. 10 to avoid confusion, but have shown the several parts on a larger scale in Fig. 12.

The rubbing contact at the end of the heavy armature a'' should be of such dimensions as to give a long contact and to break before the armature strikes the stop n''. This contact device can also be substituted for the yielding spring prolongations of the armatures of the relays at the several stations.

There would be a certain advantage in using a metallic circuit with this system, because the extremity of the line will be at the central office, thereby dispensing with the contrivances which I have described for giving a direct ground instead of through the resistance R^h, as already described.

It will be observed that as the call is given

from any station by grounding the line there, any accidental ground on any part of the line will announce itself and indicate its location on the dial.

5 To avoid the expense of two telephones at each station I employ the arrangement shown in Fig. 13. A wedge, W , made of rubber, with its sides covered with metal, as shown, is mounted so that it can move between two spring-jacks, 10 $W' W^2$. The weight of the telephone, which is hung on a hook attached to the lever, normally keeps the wedge in contact with the lowest side, and in this position the connection is suitable to talk to the main office or to any 15 station between the one in question and the central office. To talk to a station beyond, the wedge must be pushed to the upper spring-jack. The letters of this figure show, by comparison with station A of Fig. 10, how the apparatus is to be connected with the rest at the station.

No particular description of the devices shown in Figs. 2, 3, and 4 is needed further than to say that the points v and w indicate 25 the escapement-teeth of the dial-indicator, and that x and i are devices for adjusting the armatures of the relays shown. These devices are to replace the magnet M .

In using the apparatus represented in Fig. 30, the condenser, after it has been discharged by the grounding of the line at station B in the example given, remains in circuit when a current from the battery Y is sent over the line by the contact of armature a with the stop 35 or point n . In order that it may be cut out automatically, the condenser J , with its switch J^a , is placed between the coils of relay R and the stop m , as shown in Fig. 14. This figure also shows connections for employing both 40 batteries X and Y for changing the condenser. In putting the battery to line through the condenser the key Q must be kept depressed so that the — pole of battery Y will be connected with the ground, and X and Y will constitute one large battery. After the armature 45 a has moved to its contact n the key Q must be released, so that the negative pole of battery Y may be placed to line.

When the Hughes apparatus is made to 50 take the place of relay R , as shown in Fig. 12, the condenser and switch are placed between the coils of H and m'' .

Instead of employing the condenser at the central office, a small condenser may be employed at each of the stations, the position 55 occupied by them, which is the same for all stations, being indicated in Fig. 15.

The operation of these condensers in the example given is as follows: The armature of the 60 relay at station D being on the ground-contact, no current passes from X on account of the condenser. When the key at station D is depressed a direct momentary ground is made at B, so that the current from X throws the armature at stations A and B and C off to their 65 right-hand contacts, and then the battery Y

acts as usual until cut off by the closing of the circuit of station B by means of the pin Q^b . The condenser at station A in the example being charged, the relay R' is affected as if it 70 had a direct ground. The switch $s w$ is employed as before described.

The key shown in Fig. 16, which is otherwise constructed like that shown in Fig. 11, has the end of the lower branch of the fork 75 wholly made of metal, while the back part (to the left in the drawings) of the straight lever of the key bears under its lower face a sheet or band of metal, k , insulated from the rest of the lever by an insulating substance, such as 80 hard rubber. (Represented by a black line in the drawings.)

Fig. 17 shows how a contact harder than rubber, ivory, or other insulator can be obtained by boring a hole through the metallic 85 body of the upper branch of the fork and forcing or screwing in it a hollow insulating-bushing, which in turn will receive a pin or screw k' , of hard metal, against the head of which the left upper extremity of the straight lever 90 may rub. Hard contacts could also be obtained in many ways substantially the same—viz., by covering the soft insulating substance with a harder one not connected with the body of the key. A hard contact may in like manner 95 be obtained in the key shown in Fig. 11.

When the key shown in Figs. 16 and 17 is employed the line-wire L^2 , supposing the key to be located at station B, instead of connecting directly with the stop m^2 , is carried to the 100 insulated plate of the key, (preferably near the pivot,) and thence is in electric connection with m^2 through the key-levers, which are kept by the spring of the key normally in the positions shown. When this key is depressed its 105 motion not only grounds the line coming from the central office through the relay-armature a^2 and contact-stop m^2 , but also just previously breaks at the key the main line, which normally extends beyond the station. The advantage of cutting off the rest of the line before giving a new ground is well known; but its main purpose in this invention is to help to put in communication from the central office any two stations, such as B and D. 110

In the method already described of obtaining said result when all the operations had been performed as far as the moment where it remained only for station B to depress its key K^2 to put itself finally in communication with 115 both central office and station D, the line from central office was partially grounded at station D through its bell and telephone, the impulse to be caused on the condenser, induction-coil, or other well-known or suitable electric appliance at the central office was only due to the portion of the line grounded beyond station B, being momentarily short-circuited by key K^2 at station B. In some cases this impulse might be insufficient, and render 120 it necessary to have at the central office a very delicate instrument to make it sensible. Now,

by the use of this key, Fig. 16 or 17, said impulse is considerably increased as the partial grounding of the line at station D is cut off, as explained, by the first operation of said key; then the ground-connection is afterward made by further motion of said key, and an electric impulse is fully produced on the condenser, induction-coil, or other suitable appliance at the central office.

10 Instead of using the condenser before described, the arrangement at the central office represented in Fig. 18 may be employed for obtaining intercommunication between any two stations, it being used in connection with the 15 key, Figs. 16 and 17, (which, when depressed, breaks first the section of the line beyond, makes a ground, and re-establishes its own connection with the section of line beyond,) at all the stations on the line.

20 At the central office an ordinary relay, H', of about the same sensitiveness and resistance as any of the polarized bells at the stations, has one end of its coils permanently connected with the ground G. The other end of its coils 25 is connected with its front stop-contact, m h.

A section of the battery X on the side of its positive pole (to the left in the drawings) is detached from said battery. The strength of this section is about the same as that of the 30 battery Y on the side of its negative pole, (to the right in the drawings,) which is used in combination with the calling-key K². The positive pole of said detached part of battery X is connected, as before described, to electro- 35 magnet H, while its negative pole is connected with the pivot of armature a h of relay H'. The positive pole of the remaining larger part of battery X is connected to the back contact-point, n h, against which said armature a h normally rests under the force of its retractile spring. This additional feature is used and operates as follows: Let us go back to that point in the description where the central office, wishing to obtain the intercommunication between stations B and D, had given 40 warning to station B to hold its telephone for conversing with station D, and to depress its key K² an instant after hearing the click of its armature, (in its passage from ground to line contact.) These directions given, the attendant at central office puts himself, in the manner already explained, in direct communication with station D, and while he keeps depressed the knob on the dial corresponding to 45 station D he moves, by hand or by well-known or suitable means, the armature a h of relay H' from its back contact-point, n h, to its front contact-point, m h, against which he holds it until he has moved in the same manner the 50 armature a of polarized relay R from its contact n to its contact m.

By this operation a circuit is made from ground G through relay H', its front contact, m h, armature a h, smaller part (to the left in the drawings) of battery 55 X, (the rest of which is cut off at n h,) and thence through electro-magnet H, relay R,

contact m, armature a, and line, as usual, to the ground at station D, after traversing there the bell and the telephone. This current is insufficient to cause the armatures between 70 the central office and the station D to pass from their line to their ground-contacts, though it weakens their pressure against p' p², &c.

It is to be noticed here that a stroke against 75 the bell at said station (with the hammer remaining close to the gong) warns it that the main office has made the circuit ready for the next operation to be performed by station B. I will also remark here that it is not impossible for station B to know also the condition of the line, for the solid part of its armature a² will, if properly adjusted, recede at this moment from its contact p² under the influence of the weak current from the left part of battery X, although the spring at the end of said armature will still preserve its line-contact m². The assistant at the central office now lets go the dial-knob corresponding to station D, 80 brings the arm and escapement-wheel to zero, 85 and immediately depresses the dial-knob corresponding to station B.

All the operations can succeed each other rapidly, and can be automatically performed by some appropriate mechanism. The amount 95 of time for their performance can be practically ascertained once for all. It increases with the number of stations situated between the central office and the two stations to be thus mutually connected, and the warning to be given 100 by the central office to the stations is to be made accordingly.

It remains now only for station B to depress once its key K², which is of the character shown in Figs. 16 and 17. This key 105 breaks the circuit from ground G at central office to ground at station D, and releases the armature a h of relay H' at central office. The said armature severs its ground-connection at m h, and by coming, under the action of the 110 retractile spring, in contact with back-stop n h re-establishes the connection of the left part of battery X with the rest, thus restoring the battery X to its full amount.

I will here remark that by the breaking of 115 the circuit as soon as key K² is depressed the hammer of the polarized bell of station D, which was close to the gong, moves away from it, thereby warning station D that the key has just been depressed at station B, and that its 120 connection with it can begin almost immediately after such back motion of the bell-hammer has taken place, for when, by the continued depression of its key K², a ground is made at station B, the whole current of battery X will, in the manner formerly described, move the armatures a a' a² from contact-points m m' m² to their contact-points n n' n². Battery Y now, in turn, in the manner explained, brings back armature a' against its contact m'; 125 but the process stops there, as the depressing of dial-knob Q^b then brings the local battery L 130

B into action, so that the key-armature of electro-magnet M^a cuts off battery Y and grounds the line at central office. The latter is in direct communication with station B, the armature of which is now on its ground-contact, while station B is itself in direct and private communication with station D through the armature of station C, which has remained on its line-contact. All the stations beyond D, 10 being on their ground-contact, are in communication each with the adjoining one on both sides. As there is no battery now in any of the circuits, there is no possible interference. When station B has done talking with station 15 D it so advises the central office. The central office can also, while B and D are conversing, call the attention of B by working its polarized bell with its call-key, to warn it, for instance, that its time is up. The central office 20 can always, at its own wish, restore the line all through to its original condition by simply raising the dial-knob corresponding to station B in the above example. The current of battery Y restores all the armatures to their primitive 25 positions against their line-contacts, after which armature a and dial-arm can also be restored to their original positions.

Instead of cutting the battery X into two parts and connecting them and the ground-wire with the relay H' , as just described, at the central office, I can make use of the following arrangement, represented in Fig. 19: Between electro-magnet H and battery X, I place the relay H' and a high resistance, H'^r , 30 connected thus: positive pole of battery X with the pivot of armature a h , the back contact, n h , of said relay with one end of the coils of electro-magnet H, as represented, and with one end of the resistance-coil H'^r , the 35 other end of which is connected with one end of the coils of electro-magnet H' . The front-contact, m h , is connected with the other end of the coils of electro-magnet H' . It operates as follows: When brought in use the armature 40 a h is moved against its front contact, the current of battery X is forced to traverse the electro-magnet H' and the resistance H'^r , the amount of which is such as to weaken said current sufficiently to prevent it from moving any 45 of the armatures of the polarized relays on the line; but as soon as the circuit is broken, as in the former case, the armature a h of relay H' returns against its back contact, n h , first breaking the circuit for a short instant between 50 electro-magnet H and battery X, and then connecting the two latter apparatus by a circuit of practically no resistance through contact n h and armature a h . Another arrangement is shown in Fig. 20, where the connections differ in this respect from Fig. 19, that the wire which was previously connected with the front contact, m h , is now connected with the pivot of the armature a h . In this case the continuity of the circuit is 55 served, and the armature a h , when it touches back contact, n h , short-circuits the coils of the

electro-magnet H' and resistance H'^r . It is, however, to be feared that by this last plan the armature a h may return to contact m h before reaching back contact, n h , in case the break made by the key of the calling-station be of too short duration, while the plan in Fig. 19 is free from such objection. A modification of the connections is also shown in the connections in Figs. 18 and 19. The contact-point n of polarized relay R, instead of being directly connected with electro-magnet M, is connected with the lever of call-key K^y , while the back or rest contact of such key is connected with one end of the coils of electro-magnet M, the other end of which is connected with the negative pole of battery Y. This modification has the advantage of cutting off the electro-magnet M while calling a station. 75

The method just described with reference 85 to Figs. 18, 19, and 20 for establishing inter-communication between any two stations can be extended so as to enable any station to call the central office and the central office to call any station. To this end the high resistance 90 at the end of the line is dispensed with, and said end of the line is then constantly and directly grounded. The last polarized relay, instead of being more sensitive, resembles the others on the line in every respect, and the 95 key which breaks the line beyond and grounds the line at the calling-station is made use of at all the stations. At the central office everything stands as described before when at rest, except that the armature a h has been placed 100 against the front contact, m h , of relay H' , so as to put to the line only the small fraction of battery X, situated to the left in the drawings. In this condition there is through the whole line but a small current, which is insufficient 105 to move any of the armatures along the line from their line to their ground contact. When a station depresses its key the circuit is broken. The armature a h of relay H' at the central office is released and recedes against its back 110 contact, n h , thus putting all the battery X to the line. Meanwhile the depressing of the key of the calling-station, continuing, causes at said station a direct ground, and henceforth the 115 rest of the process of signaling or recording the call goes on as before, with this exception, however, that the dial-hand will indicate, Fig. 1, the number immediately after the letter indicating the calling-station, on account of the end of the line being grounded, thus giving 120 circuit to the current of battery Y, which causes the last attraction of the armature of dial electro-magnet M. 125

The process of calling a station from the central office with this arrangement is as follows: Things having resumed the position of rest, the assistant at the central office has but to first depress on the dial the knob corresponding to the station to be called and then move the armature a h from its front contact, m h , to its back contact, n h . This puts all battery X to the line from ground G at cen- 130

tral office to the last ground at the end of the line. All the polarized relay-armatures move to their ground-contacts and battery Y comes into play, and the rest of the operation goes on, as previously described for calling from the central office.

Whenever the end of the line has to be extended to one or more stations it saves time, trouble, and expense in the arrangement just described not to be obliged to remove the last extra-sensitive relay and the high resistance used at the last station, as described before, and as represented in Fig. 10. All the stations can hence be constructed alike, the last one as well as the other. The extra-sensitive relay, used formerly at the end of the line, is replaced by the extra-sensitive relay H' at the central office, and in the process last described the central office can always readily regulate the amount of small current flowing to the line, either by regulating the resistance H', if used, or by varying at will the number of cells in the smaller section or left part of the battery X, while formerly, with the high resistance at the end of the line being generally out of immediate and convenient reach, it was more difficult to obtain the same result. It will also, by the last process, become possible to use for the larger part of the battery X the kind of battery used for open circuits, while in the former arrangement, Fig. 10, this was possible only for battery Y. The smaller part of battery X to the left will, however, be preferably a constant-current battery, such as Daniell's or its modifications.

A saving in the number of cells necessary at the central office may be obtained by the last-described arrangement, for if there are several lines radiating from the central office the large part of the battery X could serve for several of them, while there could be a sensitive relay, H', with a small battery (corresponding to the small part of the battery X to the left) for each line. In this case the positive pole of the single large part of battery X would be connected with all the back contact-points of each relay, like H'.

With the last-described arrangement there is no use of condenser or induction-coil or switch s w either at the central office or at the way-stations.

I will also here remark that, while a lasting ground occurring on the line in the system shown in Figs. 1 and 10 would be signaled and located on the dial at the central office, (which operation can be readily understood, and is an important feature of the system,) said ground would not show on the last-described plan unless it was preceded by a breaking of the circuit, such as can take place when a line breaks and falls to the ground, which is then a noticeable feature of the latter plan. In the former system an accidental break not followed by a ground would not be signaled otherwise than by the well-known use of the galvanometer, and such break would not be

located. In the latter plan an accidental break not followed by a ground would be indicated by the armature a h falling on its back contact.

In the system as shown in Fig. 10 the nature of the accidental ground is readily known at the central office. If the ground is of long duration, or permanent, the dial-hand will stay on the number following the letter representing the station beyond which the ground has occurred, and as soon as the attendant at the central office replaces the apparatus at the state of rest they reassume their former positions, the dial-hand showing again the same number. On the other hand, if the ground has only been temporary, the apparatus, once replaced in the state of rest at the central office, keeps it, unless there is a periodical ground arising from what is known in telegraphy as a "swing," in which case the dial-hand will have to be replaced every time it has indicated it. At all events the nature of the ground is known, as aforesaid.

In Fig. 21 is shown an apparatus something like a Siemens' shuttle, which can advantageously replace relays with the spring prolongation of the armature. The current passes through the shuttle S^h, instead of through the armature. The line and ground contact points are indicated by m' n', as heretofore. This arrangement has the advantage of rendering the line and ground contacts steady during the passage of the armature proper from one side of the shuttle to the other, while when a spring is used at the end of the tongue the quality of the contacts varies with the variable pressure of the spring during the movement of said tongue. The small wheel fixed at the end of a spring on the pivoted part of the shuttle serves to maintain said shuttle steady against either one of its limiters. Its position and pressure are adjustable.

In Fig. 22 is represented one manner of varying the contacts and connections so that the shuttle will make the double contacts made by the armature at a station, as in Fig. 10, for the purpose of intercommunication. Fig. 23 represents another manner of obtaining the double contact just referred to. In these figures the parts in black represent hard rubber or other insulating material. The lettering is made for convenience to correspond with the apparatus at station A. In Fig. 22 the spring or plate t corresponds to the insulated plate attached to the armature in the relay shown in Fig. 10, and is therefore lettered the same. In Fig. 23 the armature itself acts in place of said plate to establish the circuit between m' and telephone T*.

It is obvious that various modifications other than those described and within wide limits could be made in my system without departing from the spirit of this invention. For example, instead of having the magnet M connected with the negative pole of battery Y, it could, if a polarized or equivalent magnet were employed, be placed, under some circum-

stances, in the ground-connection from the positive pole, or, in fact, in any desired position, so that the coils thereof would be traversed by the current from battery Y. I do not, therefore, intend to limit myself to the details of the apparatus described.

Having thus fully described my said invention and the manner in which the same is or may be carried into effect, what I claim, and desire to secure by Letters Patent, is—

1. In an electrical system comprising a central office and several stations, the method of calling the central office from any station by pressing a key at said station, and thereby causing a current of one polarity to ground the line at every station and to make a contact which throws upon the line from the central office a current of opposite polarity, which successively breaks the ground-connection and restores the line-connection at each station until the calling-station is reached, each such make and break and consequent flow and intermission of current operating to move or control an indicating apparatus at the central office, substantially as described.

2. In an electrical system comprising a central office and several stations, the method of establishing communication from the central office with any desired station to the exclusion of others by causing a current of one polarity to ground the line at every station and to make automatically a contact which throws upon the line from the central office a current of opposite polarity, which successively breaks the ground-connection and restores the line-connections at each station until such battery be cut off, and stopping the operation of such battery by suitable means when it has restored the line-connections up to the station to be called, substantially as described.

3. In an electrical system having a central office and a number of stations arranged on a circuit normally connected with a source of electricity too weak to operate the instruments, the method of operating said instruments from any of the stations by a battery or batteries located at the central office, consisting in altering the electrical condition of the line and breaking the line and making a ground-connection at a station by depressing a suitable key, and thereby increasing the current on the line, as described.

4. In an electrical system comprising a central office and several stations, a closed circuit normally of considerable resistance connected with a source of electricity too weak to operate the instruments at the stations, in combination with circuit-closing devices for forming a new ground-connection of less resistance at the end of the line by the operator at the central office or at any of the stations by the operator at said station, substantially as described.

5. In an electrical system comprising a central office and several stations located on the

same line, the method of putting the stations in private communication with the station on either side, consisting in breaking the line and grounding both ends thereof at all the stations by a current from the central office, and thereby establishing a ground-circuit from each station in either direction over the line over which communication may be had by suitable instruments, such as telephones.

6. In an electrical system, the method of connecting two stations on the same wire in a practically private circuit by grounding the line at all the stations by one current of electricity, restoring the line by another current to the station more distant from the central office, then grounding the line at the other station and connecting also with the ground that portion of the line leading to the more distant station, substantially as described.

7. In an electrical system in which a number of stations are connected with a central office by a line-wire, the method of establishing a practically private line between two stations, at the same time maintaining a separate circuit with the central office from the one nearest the central office by grounding the line at all the stations by a current of one polarity, restoring the line to the station more distant from the central office by another current of different polarity, grounding the line at all the stations between the central office and the nearest station, and including the latter, by the depression of a key at that station, which causes the passage of the required current, and restoring the line to the nearest station, but not including it, by a current of different polarity sent and controlled from the central office, substantially as described.

8. A system for telephonic or other electrical communication in which two or more stations are located upon a line or circuit connected with a central office, whereby any station can call the central office and register itself thereat, as set forth, the said system consisting of the combination of the following elements, to wit: at the central office two batteries, or a battery adapted to have opposite poles put, in turn, to line, a polarized relay, an electric indicator or other signaling or registering apparatus, and connections, as shown, and at the several stations a polarized relay, a key, a ground-wire, and connections, substantially as described.

9. The combination, in an electric system in which a central office is connected with a number of stations on a single line, of a series of polarized relays located at the several stations, having their circuit-breaking armatures movable between line-contact stops and stops connected with ground-wires, the line-wire connected with the coils and armatures and with the line-contact stops, a battery or batteries, and devices, as indicated, for putting to line-currents of opposite polarity, substantially as described.

10. The combination, in an electrical system

having a central office and a number of stations connected by a line-wire, of two batteries, or a battery adapted to have opposite poles put, in turn, to line, a polarized relay and connections, as shown, at the central office, with a polarized or equivalent relay having its armature and coils connected permanently with the line-wire, and a line-contact and a ground-contact stop, between which the armature moves at the several stations, substantially as described, whereby the passage of an electric current of one polarity over the line moves the armatures at the stations to their ground-contacts, and automatically, through the movement of the relay at the central office, puts to line a current of opposite polarity, which successively returns the armatures to their line-contacts, as set forth.

11. The combination, in an electrical system having a central office and a number of stations connected by a line-wire, of a battery or batteries, a polarized relay and connections, as shown, at the central office, a polarized relay with its armature movable between a line-contact stop and a stop connected with the ground, and a key or circuit-closing device for connecting the line-contact stop with the ground, located at each station, and a line-wire connected with the armature of the relay at the central office and with the coils, armatures, and line-contact stops at the several stations, substantially as described.

12. In an electrical system consisting of a central office and several stations connected by one line-wire and provided at the central office with two batteries and an annunciating apparatus, the combination of a polarized relay at the central office, having its armature permanently connected to line and movable between two contact-stops, with the polarized relays at the several stations, having their armatures each connected with the coils of its relay and the line, two contact-pieces and a key for each relay, and connections, whereby the closing of the circuit by means of a key at any station will operate the annunciator and then automatically break the circuit and throw a current of opposite polarity to the line from a battery at said central office, as set forth.

13. The combination, with a key, of a polarized relay having the armature permanently connected through the coils of the relay with a line-wire and moving at its free end between contact stops or points, the said stops or points being connected, one with a conductor to form a continuation of the line which has passed through the coils and armature of the relay, and also with the key-lever, and the other with the ground, the aforesaid key making a ground by its contact, substantially as described.

14. The combination, with two batteries or a single battery, a polarized relay, its armature, and contact-stops between which the end of the latter moves, of the electrical connections, as set forth, whereby the battery-current of one polarity, through the coils and ar-

matures of the polarized relay to a line-wire, breaks the circuit of that current and automatically establishes the circuit for the passage to the line of a current of opposite polarity, substantially as described.

15. The combination, with two batteries or a single battery, a polarized relay, its armature, and contact-stops between which the end of the latter moves, and an electric indicator or other signaling or registering apparatus, of electrical connections, whereby a battery-current of one polarity, through the coils and armature of the polarized relay to a line-wire, breaks the circuit of that current and establishes a circuit for the passage of a battery-current of opposite polarity through the indicator to the line, substantially as described.

16. The combination of a battery or batteries, an alarm or annunciating apparatus, a polarized relay with its armature connected to line, and two contact-stops, connected as set forth, one through the coils of the relay and the magnet for operating the annunciator with one pole of the battery, and the other with the opposite pole, whereby the current passing to the line through the coils of the relay operates the annunciator, moves the armature of the relay, and automatically puts to line the current of opposite polarity, substantially as described.

17. The combination, with a Hughes or other electro-magnet, of an audible or visible signal, or both, operated thereby, and electrical connections for passing a battery-current of one polarity through the coils and armature of said magnet, the circuit of which current is broken by the movement of the armature, and for completing by the same movement a circuit for a battery-current of opposite polarity, substantially as described.

18. The combination, with the parts of a telephone or telegraph system having a central office and two or more stations located on a single line, and in which the movements of the relays located at the several stations operate to cut off or add sections of the line, of artificial compensating resistances, arranged as set forth, to be automatically introduced or omitted by the action of the relays, substantially as described.

19. The combination, with the pointer of an electric dial-indicator or similar part of other signaling or registering apparatus, of an artificial resistance connected in the circuit through the indicator, and arranged as set forth, to be diminished by the movement of the pointer from the zero or unison position, substantially as described.

20. The special key consisting of an operating-lever provided with an insulating-knob and a forked lever provided with insulated and conducting contact-points, arranged to operate in connection with the first lever, substantially as described.

21. The special key consisting of a forked lever and an operating-lever with contact-stops, as described, in combination with a me-

tallic plate connected with the operating-lever, but insulated therefrom.

22. In an electric system, the combination, with a line-wire and a branch or ground wire, of a key composed of a forked lever and an operating-lever with contact-stops, as described, the forked lever being connected with the line-wire, and the operating-lever with the branch or ground wire, whereby one movement of the key makes for a moment and then breaks an electrical connection between the line-wire and the branch or ground wire.

23. In an electrical system, the combination of a key composed of a forked lever and an operating-lever and insulated and metallic contact-stops, as described, a metallic plate connected with said operating-lever, but insulated therefrom, a line-circuit completed normally through said key by connections with the forked lever and the insulated plate, and a branch or ground wire connected with the operating-lever, substantially as set forth.

24. In a telephone or telegraph system having a central office and stations located on the same line, and in which the calling of the central office and the indications thereat are effected by currents of opposite polarity acting upon a series of polarized or equivalent relays, and in combination with the relays, batteries, and connections of such system, a series of keys located at the stations and making, when operated or depressed, a momentary contact and then breaking said circuit, substantially as described.

25. The combination, with a circuit fitted for the passage of electrical currents or electrical impulses, of a series of polarized relays located at stations on said circuit, which passes through the armatures of the relays, the line and ground contact stops between which said armatures are movable, and means, substantially as described, for putting upon the circuit a current of the polarity required to move the armatures of the relays from their line-contacts to ground-contacts, for putting upon the line a current of opposite polarity, whereby the armatures are restored *seriatim* to their line-contacts, and for leaving the line free at the required moment, whereby a circuit may be established with any station from a central office at which the aforesaid means are located, as set forth.

26. The combination, with an electric dial-indicator or other suitable signaling or registering apparatus, a battery, and the circuit from said battery through the electro-magnet by which the said indicator is operated, of devices, as set forth, for automatically breaking the circuit from the aforesaid battery when the pointer of the indicator has reached the required position, substantially as described.

27. In a telephone or telegraph system, the combination, with the pointer of an electric indicator, of an arm in advance of said pointer, a series of conductive pins with insulated heads, connected with one pole of a local battery-circuit and adapted to be depressed into

the path of the aforesaid arm with which the other pole of the local circuit is connected, substantially as described.

28. The combination, in a telephone or telegraph line, of a series of polarized relays whose armatures form a part of the line-circuit and move between line-contact and ground-contact points, and a polarized relay whose armature forms a part of the line-circuit and moves between contact-points, of which one is connected through the coils of the relay with a battery of the polarity required to move the armatures of the series of relays from their line to their ground contacts and its own armature from its point connected with the battery, and the other, through an electric indicator or other signaling or registering apparatus, with a battery of the opposite polarity, and devices, as set forth, adapted to be set to automatically leave the line free from current sufficient to operate the relays when the desired condition of the line is indicated by the signaling or registering apparatus, substantially as described.

29. The combination, in a telephone or telegraph line, of a series of polarized or equivalent relays whose armatures form part of the line and move between line and ground-contact points, a series of electric alarms or other signaling devices located in the wires from the aforesaid ground-contact points, a polarized relay whose armature forms a part of the line and moves between contact-points, one connected through the coils of the relay with a battery of one polarity and the other through an electric indicator with a battery of opposite polarity, devices for cutting out both said batteries to leave any desired station in circuit, and means, as indicated, for operating the alarm or signal at that station without affecting the armatures of any of the aforesaid relays, all substantially as described.

30. The combination, in a telephone or telegraph line, of a series of sluggish relays, each arranged to complete the line to stations more distant from the central office, or to put it to ground, according to the polarity of the passing current, a series of alarms or calls located in the ground-wires from said relays, an electric indicator, and means, substantially as set forth, for putting upon the line a current of the polarity required to move the armatures of the relays to form a ground-connection at each station, for putting upon the line a current of opposite polarity to restore the armatures *seriatim* to complete the line, station by station, for automatically breaking the current when the line is completed to the desired station, and for operating the alarm or call in the ground-wire of that station without affecting the relays, as described.

31. The combination, with the armature of a polarized relay with contact-points and connections for completing a line through the station at which it is placed or for grounding it thereat, of a conducting-plate carried by, but insulated from, said armature, a point or stop with which the said plate makes contact when

the line is grounded, and electrical connections from said point or stop to the line beyond said armature and from the insulated plate to the ground, substantially as described.

5 32. The combination, in a telephone or telegraph system, with a series of relays arranged at suitable distances or stations on a closed circuit, fitted for the passage of an electric current or electric impulses, and passing through the 10 armatures of the relays to contact-points on one side, those on the other side being grounded, a battery of sufficient of strength to operate said relays, and a key or other device to put said battery to line, so as to move said armatures 15 to their ground-contacts, of means, substantially as set forth, for establishing a circuit between each station and a station on either side thereof.

33. The combination, with two spring-jacks 20 connected with different circuits, of a wedge of insulating material, with metallic sides, working between said spring-jacks and having both ends adapted for insertion in said jacks, whereby a telephone and other instrument for 25 communicating by electricity having its wires connected with the metallic sides may be readily connected with either of said circuits, substantially as described.

34. The combination, in a telephone or telegraph system, of a series of relays arranged 30 on a circuit having its line on one side connected through the coil of each relay with the armature and on the other with a stop, so that the line is closed when the armature makes 35 contact with it, a battery or batteries, devices, as indicated, for putting on the line the currents required to break the contact of all of 40 said armatures with their line-stops or to restore them thereto *seriatim* until a desired 45 relay has been affected, and means, substantially as described, for establishing ground-connections at each relay with both ends of the line when it is broken by the absence of contact with its line-stop of the armature of said relay, substantially as described.

35. The combination, in a telephone or telegraph system, of a series of relays, a line-wire connected through the coils and armature of each relay and by means of a contact-stop 50 with the next relay to the end of the series, a ground-wire at each relay connected with a stop, with which the armature of that relay makes contact after the line-contact has been broken, an alarm or call or other instrument for giving 55 intelligence, located on each ground-wire, a second ground-wire at each relay and means for connecting it after contact of the armature at that relay with the line-stop has been broken with the broken end of the line, one or 60 more batteries and devices, as set forth, for putting upon the line the currents of the polarity respectively required to operate said relays, so as to break and ground the line-wire at each relay or to restore the armatures 65 *seriatim* to their line-contacts until the desired relay has been affected, and for operating the alarm or otherwise establishing com-

munication with any station at which the necessary condition of the line is obtained, as aforesaid, without affecting the relays, substantially as described.

36. The combination, in a telephone or telegraph system having a central office and two or more stations, of a line-circuit completed through a series of polarized relays located at 75 the stations by contact of the armatures of the relays with line-stops, batteries, keys, or circuit-chargers, and electrical connections for establishing by the aid of said relays a practically private circuit from the central office 80 to any station, and for calling or communicating with that station without affecting the relays and devices, as set forth, for calling the central office from any station, substantially as described.

37. The combination, in a telephone or telegraph system having a central office and two or more stations, of a line-circuit completed through a series of polarized relays located at 90 the stations by contact of the armatures of the relays with line-stops, batteries, keys, or circuit-chargers, and electrical connections for establishing by the aid of said relays a practically private circuit from the central office to any station, and for calling or communicating 95 therewith without affecting the relays, an indicator or other signaling or registering apparatus at the central office, and devices, as described, for calling the latter from any station and indicating or registering the calling-100 station by said indicator apparatus, substantially as set forth.

38. The combination, in an electrical system having a central office and a number of stations, of a relay, a ground-wire, and a suitable 105 key at each station, a circuit fitted for the passage of an electrical current or an electrical impulse passing through the relays, a battery or batteries at the central office, and apparatus located at the central office or at suitable 110 points on the circuit, such as an electro-magnet operated by a temporary break in the circuit for causing, by the aid of the battery or batteries at the central office, a current of sufficient strength to work the relays to traverse 115 the line between the central office and any station by the depression of the key at that station, substantially as described.

39. In an electrical system comprising a central office and a number of stations, in which 120 each station is provided with a polarized relay through the coils and armatures and line-contact stops of which the line-circuit passes, and also with a ground-wire and a suitable key or circuit-charger, and the apparatus whereby, 125 when a circuit is established from the central office to one station, an intermediate station can, by depressing its key, move the armatures of its own and preceding relays to ground and automatically restore to their line-contacts the 130 armatures of relays between itself and the central office, the said apparatus consisting of devices such as a condenser and switch or electro-magnet and armature for sending to line a

current of the polarity and strength required to move the armatures of the relays to their ground-contacts by the alteration in the electrical condition of the line or break due to the depression of the key, a battery or batteries, a polarized or equivalent relay, and connections, as described.

40. The combined telephone or telegraph system hereinbefore described, comprising relays or electric switches and keys at the several stations, and batteries, circuit-chargers, and annunciating or indicating apparatus at the main office, whereby any station can call the main office and register itself thereat, and 15 a practically private line under the control of the main office can be established between the main office and any station or between two stations, substantially as set forth.

41. In an electric circuit, an electric switch 20 capable of being operated from a distant station to break the circuit and connect the separated portions with independent branches to ground, substantially as described.

42. The combination of a battery or batteries, an apparatus, such as a condenser and switch, or electro-magnet and armature, for sending to line a current of the required strength by an alteration in the electrical condition or a break in said line, a relay, an 25 alarm or annunciating apparatus connected in the same circuit with said relay, an indicator, an electro-magnet connected in a local battery-circuit, devices capable of setting and adapted to close said local circuit by the movement of the pointer of the indicator to the 30 proper position, a key arranged as the armature of said magnet, and connections, substantially as described.

43. In an electrical system having a central 35 office and a number of stations connected with each other, the combination of a polarized relay with its armature movable between a line-contact stop and a stop connected with a ground-wire, the line-wire connected with 40 the coils and armature of the relay and with the ground-contact stop, a key or circuit-closing device for grounding momentarily at will that portion of the line-wire connected with the line-contact stop, and a call-telephone or 45 other instrument for giving or conveying intelligence by electricity, connected with the aforesaid ground-wire, all of said devices being located at each of the stations, with a polarized relay having its armature connected 50 with the line-wire, a battery or batteries having one pole connected through the coils of 55 the relay with a contact-stop of its armature and the opposite pole with the other stop, a ground-wire adapted to serve as a ground-connection for a battery-current of either polarity, a key or circuit-closing device for sending at will a current from the battery through 60 the coils of the relay over the line, an electro-magnet arranged to be operated by currents

passing to line through the armature of the 65 relay and its last-named contact-stop, an apparatus operated by said electro-magnet by the makes and breaks of a current passing through its coils, and adapted to be set to cut out the battery from line after a determined 70 number of makes and breaks have been made, and an electrical instrument or instruments for giving or conveying intelligence, all located at the central office, as set forth.

44. In an electrical system having a central 75 office and a number of stations connected by the same line, the combination of a polarized or equivalent relay, a key or circuit closing and breaking device, an instrument or instruments for receiving or transmitting intelligence by electricity, a conducting-plate connected with the armature of the relay, but insulated therefrom, and connections, as set forth, with the line-wire and with the ground at each station, and a polarized relay, a battery or batteries, an annunciating apparatus, a dial-indicator or other signaling or registering apparatus, and mechanism connected therewith for automatically cutting off the current from the line after a determined movement of the indicator, a key or circuit-closing device, and connections, as shown, at the central office, all substantially as and for the purpose described.

45. In an electrical system having a number 95 of stations connected with a central office by the same wire, the combination of devices, such as a condenser and switch, or electro-magnet and armature, for sending a current to line by a break or alteration in the electrical condition of said line, a polarized relay with armature movable between contact-stops, an annunciating apparatus, a dial-indicator or other signaling or registering apparatus, a battery or batteries, mechanism for automatically breaking the battery-circuits by the operation of the indicator or registering apparatus, a call-key or circuit breaking and closing device, and connections, as set forth, at the central office, and a polarized or equivalent relay with its armature movable between contact-stops, a conductive plate attached to 100 said armature, but insulated therefrom, movable into and out of contact with a suitable stop, a key or circuit closing and breaking 105 device, an instrument or instruments for the transmission or reception of intelligence by the aid of electricity, and connections with the line-wire and with the ground, substantially as described.

In testimony whereof I have signed this specification in the presence of two subscribing witnesses.

GEORGES D'INFREVILLE.
